UNITED STATES PATENT OFFICE.

FREDERICK GOERTZ, OF SOUTH ORANGE, AND WALTER A. GOERTZ, OF EAST ORANGE, NEW JERSEY, ASSIGNORS TO AUGUST GOERTZ & CO. INC., A CORPORATION OF NEW JERSEY.

COSMETIC BOX.

Application filed March 13, 1928. Serial No. 261,252.

This invention relates to improvements in cosmetic boxes or vanity cases; and the invention has for its principal object to provide a simple construction and assembly of 5 parts comprising a body and cover sections hinged together and a novel construction and arrangement of means to retain said sections in closed relation, and also novel means to mount and retain a mirror within the cover 10 section of the box or case.

Other objects of this invention, not at this time more particularly enumerated, will be fully understood from the following detailed 15 description of the same.

15 The present invention is clearly illustrated in the accompanying drawings, in which:—

Figure 1 is a top plan view of the box or case closed; Figure 2 is a top plan view of the box or case opened; Figure 3 is a plan 20 or face view of a mirror retaining frame detached from the box or case; Figure 4 is a fragmentary plan view enlarged showing in part the means for assembling and holding the mirror retaining frame at the hinge side 25 of the cover section; Figure 5 is a transverse section, taken on line 5—5 in Figure 4; Figure 6 is a transverse section enlarged showing in part the means for assembling and holding the mirror retaining frame at 30 the outer free side of the cover section; Figure 7 is a horizontal section, taken on line 7—7 in said Figure 6; and Figure 8 is an enlarged transverse section, taken on line 35 8—8 in Figure 1.

Similar characters of reference are employed in all of the hereinabove described views, to indicate corresponding parts.

Referring now to said drawings, the reference character 10 indicates a body section 40 and 11 a cover section of a cosmetic box or vanity case, said sections being of substantially concavo-convex formation. Said body section 10 is provided along one edge portion with a plurality of spaced apart fully closed hinge knuckles 12, and similarly the cover section 11 is also provided with hinge knuckles 13 positioned to engage intermediate the knuckles 12 of said body section, and to be aligned therewith when said sections 45 are assembled one with the other. A hinge pintle P is passed through said aligned hinge knuckles 12 and 13 to pivotally interconnect said sections so that the same may be closed together one upon the other. Certain of

55 said hinge knuckles 13 of said cover-section are formed by tongues integral with the edge of the body thereof from which they spring, and said tongues are bent around into substantially cylindrical form but with their free ends terminating short of the body so 60 as to provide recesses 14 on the inner sides of said knuckles, i. e. toward the interior of said cover section, said recesses being bounded at the ends thereof by the adjacent 65 fully closed hinge knuckles 12 of the body section 10.

Backed against the interior face of said cover section 11 is a mirror 15 which forms one of the features common to cosmetic boxes or vanity cases. This mirror 15 is retained 70 in assembled relation to said cover section by a novel construction and arrangement of retaining frame 16 having means to positively and securely interlock the same with and into said cover section. Said retaining frame 16 is adapted to be engaged over the marginal portions of said mirror 15, the outer marginal portions of the frame 16 being shaped to conform to the interior 75 marginal contours of the cover section, and 80 said frame having a central opening through which the mirror is exposed. Integrally formed with an edge of said retaining frame 16 which is adapted to be disposed along the hinged side of the cover section 11 are 85 keeper tongues 17, which, when the frame is inserted in place within the cover section enter within said recesses 14 formed by certain of the hinge knuckles 13 in the manner above described. By this arrangement 90 one side of the frame 16 is interlocked with the cover section against displacement from operative assembled relation thereto. Integrally formed with the opposite edge of 95 said retaining frame 16 which is adapted to be disposed along the outer free side of the cover section 11 are outwardly extending projections or lugs 18. The marginal portions of said outer free side of the cover section 11 is provided with perforations or 100 openings 19 corresponding in position to the position of said lugs 18 of the frame, and into and through which the latter may be sprung to thereby interlock said opposite side of the frame 16 with the cover section 11 against 105 displacement therefrom. It will thus be apparent that the frame 16 may be quickly and easily assembled in retaining

relation to the mirror 15 and firmly and securely held against displacement from the cover section in a very simple and efficient manner.

5 The retaining frame 16, when assembled and interlocked to and with the cover section 11 of the box or case not only securely holds the mirror 15 in place, but also provides a decorative bounding finish for the 10 mirror, while at the same time the construction is such that but a minimum portion of the interior space of the box or case is taken up by the mirror and its retaining means, and consequently a relatively thin box may 15 be provided which nevertheless furnishes adequate containing space for cosmetic compact and associated puff which the complete box or case is designed to carry.

20 The means for holding the body and cover sections of the box and case in closed together relation, comprises a fixed exteriorly projecting catch-stud or nosing 20 which is centrally secured to the outer free side of the body section 10. Pivottally affixed to the 25 outer free side of the cover section 11 is a catch plate 21 having adjacent to its free end a slot 22 to receive said catch-stud or nosing 20 when the catch-plate 21 is swung down into engaged relation to the latter. 30 The means for pivotally engaging said catch-plate 21 with the cover section 11 comprises a fulcrum tongue 23 which projects from the cover section and through a transverse slot 24 of the catch-plate 21, the free 35 end of said fulcrum tongue 23 being turned over the adjacent upper end of the catch-plate, all whereby the tongue forms a bearing or fulcrum support relative to which the catch-plate may swing or turn toward or 40 away from the catch-stud or nosing 20. This novel form of catch is very positive and yet is exceedingly easy to manipulate; furthermore, the same is not subject to accidental opening under internal strains exercised by a powder puff compressed within 45 the closed box or case.

50 From the above description it will be understood that this invention provides a very simple and yet compact and easily assembled box or case comprising but a minimum number of parts.

Having thus described our invention, we claim:

1. In a vanity case having cooperating sections, each section having hinge knuckles respectively adapted for alternated aligned disposition when the sections are cooperatively assembled, a pintle extending through said knuckles, certain of said hinge knuckles of one section being arranged to provide recesses facing the interior of said section, a mirror disposed on the inner side of said latter section, a retaining frame to hold said mirror in place, said retaining frame having on one side projecting tongues engaged in 60 said recesses, and interengaged male and female means connected with the opposite side of said retaining frame and said section. 65

2. In a vanity case having cooperating sections, each section having hinge knuckles respectively adapted for alternated aligned disposition when the sections are cooperatively assembled, a pintle extending through said knuckles, certain of said hinge knuckles of one section being arranged to provide recesses facing the interior of said section, a mirror disposed on the inner side of said latter section, a retaining frame to hold said mirror in place, said retaining frame having on one side projecting tongues engaged in 70 said recesses, and interengaged male and female means connected with the opposite side of said retaining frame and said section. 75

3. In a vanity case comprising a body section and a cover section having interfitting hinge knuckles at adjoining sides, a pintle engaged through said hinge knuckles, certain of said hinge knuckles of said cover section having open portions toward the interior of said section to provide recesses, the marginal portion of said cover section opposite its hinged side having openings therein, a mirror disposed within said cover sections, and a retaining frame to engage the 90 marginal portions of said mirror, said retaining frame having marginal projections for entrance in said recesses and openings whereby said frame is interlocked in assembled relation to cover section and in 95 holding relation to said mirror. 100

In testimony, that we claim the invention set forth above we have hereunto set our hands this 12th day of March, 1928.

FREDERICK GOERTZ.
WALTER A. GOERTZ.
